UNITED STATES PATENT OFFICE.

JOHN CHARLES BAUER, OF LONDON, ENGLAND.

DIE-STOCK.

SPECIFICATION forming part of Letters Patent No. 330,868, dated November 24, 1885.

Application filed April 23, 1885. Serial No. 163,153. (No model.) Patented in England March 17, 1884, No. 5,001; in Belgium September 4, 1884, No. 66,218; in France October 9, 1884, No. 164,711; and in Austria-Hungary December 3, 1884, No. 37,163 and No. 56,675.

To all whom it may concern:

Be it known that I, JOHN CHARLES BAUER, a subject of the Queen of Great Britain, residing at London, England, have invented 5 certain new and useful Improvements in Die-Stocks, of which the following is a specification.

This invention relates to improvements in stocks and dies, the improvements having 10 chiefly for object to combine in one tool an entire set of adjustable dies, with simple means for adjusting the same.

In carrying out my invention I employ two disks turning on centers or pivots, one of 15 which is eccentric. Around the periphery of each disk, and at suitable distances apart, I form the cutting-threads in such a manner that when the disks are properly adjusted the corresponding threads to form a pair of dies 20 will be brought into working position. The disks are held together and in position by a plate or plates and by screws on the pivots of the disks.

The tool is provided with suitable handles, 25 and in place of employing an eccentric pivot operated by a spanner, I can employ screws to tighten up the disks.

In order to enable my invention to be fully understood, I will proceed to describe the 30 same by reference to the accompanying drawings, in which—

Figure 1 is a plan, Fig. 2 a horizontal section, and Fig. 3 a longitudinal vertical section, of a stock and dies constructed according 35 to my invention, and in which one of the disks turns on an eccentric pivot and the other disk on a concentric pivot. Figs. 4, 5, and 6 are similar views to Figs. 1, 2, and 3, but in which both disks turn upon concentric 40 pivots. Figs. 7, 8, and 9 are also similar views to Figs. 1, 2, and 3, but showing an arrangement in which the disks are caused to approach each other by means of screws.

Similar letters in all the figures represent 45 similar parts.

I will first describe my invention by reference to Figs. 1, 2, and 3.

a and *a'* are the two disks, and *b* and *b'* are the centers or pivots on which the disks *a* and 50 *a'* turn, the pivot *b'* being eccentric to its cor-

responding disk, *a'*. *c c c* are the cutting threads or dies formed at suitable distances apart around the periphery of each of the disks *a* and *a'* in such a manner that when the disks are properly adjusted by rotating 55 the same the corresponding threads to form a pair of dies will be brought into working position. *d d* are the plates and *e e'* the screws serving to hold the disks *a* and *a'* in position between the handles *d' d'*. The 60 screws *e* and *e'* may be formed on the pivots *b* and *b'* in the manner shown, the screw *e* having a hexagonal head, and the screw *e'* having a nut for clamping the disks *a* and *a'*. The eccentric pivot *b'* is formed with a square 65 end, as clearly shown in Fig. 1, to operate its eccentric part. *f f* are openings in the plates *d d* to admit of the insertion of the bolt, pipe, or other article on which the screw-thread is to be cut.

To adjust the dies, (the plates and disks being clamped,) the disks *a* and *a'* are slackened by turning the screw *e* and the nut of the screw *e'* by a spanner or otherwise. The required pair of dies, *c*, are then brought into 75 position by turning the disks *a* and *a'*, which are then again clamped. The eccentric pivot *b'* is then turned, and the pair of dies will be thereby closed into their cutting position.

The arrangement shown in Figs. 4, 5, and 80 6 is similar to that hereinbefore described, and represented in Figs. 1, 2, and 3, with the exception that both the pivots of the disks *a* and *a'* are concentric. The lower plate, *d*, is dispensed with, and the upper plate is shown 85 formed in one piece with the handles *d' d'*. The operation is also similar to that hereinbefore described, except that as there is no eccentric pivot in this arrangement both the disks are adjusted concentrically only.

In the arrangement shown in Figs. 7, 8, and 9 the dies are adjusted in a similar manner to that hereinbefore described when referring to Figs. 1, 2, and 3; but the pair of dies are closed into their cutting position by means of 95 rods *g g* within the handles *d' d'*, and operated by screw-caps *h h*, the said rods having crutch-shaped ends to form an even bearing against the disks *a* and *a'*. The holes in the plate *d* in which the pivots *b* and *b'* have their 100

bearing are elongated to allow of this lateral movement of the disks a and a' .

It will be understood that although I have shown the screw stock and dies represented in Figs. 1, 2, and 3 as having two plates, d d' , I may in some cases dispense with one of the said plates.

Having now particularly described and ascertained the nature of my said invention and in what manner the same is to be performed, I declare that what I claim is—

1. In a screw stock and dies, a pair of rotatable disks, each provided with corresponding screw-cutters of different sizes, as described, in combination with a shaft jour-

naled in the stock, the shaft having thereon an eccentric, which serves as the journal of one of the said disks, substantially as shown and described.

2. In a screw stock and dies, the combination, with the disks a a' , each provided with cutting-threads of various sizes, of adjustable rods g , inclosed within the handles, and having inner curved ends, as set forth, having screw-caps for operating said rods, all substantially as hereinbefore described. 20 25

J. C. BAUER.
